UNITED STATES PATENT OFFICE.

HANS PETERSEN, OF MILWAUKEE, WISCONSIN.

DESIGN FOR AN AUTOMOBILE SIGNAL LAMP.

Application filed April 26, 1923. Serial No. 5,965. Term of patent 7 years.

To all whom it may concern:

Be it known that I, HANS PETERSEN, a citizen of the United States, residing at Milwaukee, in the county of Milwaukee and State of Wisconsin, have invented a new, original, and ornamental Design for Automobile Signal Lamps, of which the following is a specification, reference being had to the accompanying drawing, forming part thereof.

Figure 1 is a side view; Figure 2 is a perspective view, and Figure 3 is an end view of my new design. The said side view and the said perspective view disclose the obverse and reverse faces of the aforesaid original, and ornamental Design for Automobile Signal Lamps, of which the following is a specification, reference being had to the accompanying drawing, forming part thereof.

I claim:

The ornamental design for a automobile signal lamp, as shown.

HANS PETERSEN.
